United States Patent Office

Des. 179,186
Patented Nov. 13, 1956

179,186

PORTABLE RADIO RECEIVER

Jack Briskin and Carl W. Claras, Chicago, Ill., assignors to Revere Camera Company, Chicago, Ill., a corporation of Delaware

Application March 26, 1954, Serial No. 29,696

Term of patent 3½ years

(Cl. D56—4)

The figure is a perspective view of a portable radio receiver embodying the invention.

The dominant feature of the design resides in the portions shown in full line in the accompanying drawing.

We claim:

The ornamental design for a portable radio receiver, as shown and described.
